LOUIS SIMON FRAPPIER AND EWALD BOECKING, OF BROOKLYN, NEW YORK, ASSIGNEES
TO INTERNATIONAL PROJECTOR CORPORATION, OF NEW YORK, N. Y., A CORPORA-
TION OF DELAWARE

FRICTION DEVICE FOR MOTION PICTURE PROJECTION MACHINES

Application filed April 22, 1929. Serial No. 356,997.

This invention relates to reeling devices, and more particularly, to a frictional take-up mechanism adapted to apply a substantially uniform tension to the material on a reel.

The invention relates more specifically to a reel for a motion picture projection machine in which the film is fed at a constant speed and at a substantially uniform tension. The invention may, however, be applied to other types of reels and winding apparatus as will be apparent to a person skilled in the art.

An object of the invention is to provide a frictional device which is capable of frictionally opposing the action of the reel with a force dependent upon the weight of the material carried thereon.

Another object is to provide a frictional reeling device which is capable of maintaining the material supported by the reel at a substantially uniform tension regardless of the diameter of the material so carried.

A further object of the invention is to so vary the frictional force applied to a reel with respect to the speed of rotation of the reel and the diameter of the material carried thereon that a substantially uniform tension is applied to said material in reeling and unreeling.

Still another object is to provide a variable frictional retarding device for a reel and means for controlling the friction thereof for causing said device to act as a brake.

A feature of the invention is a frictional clutch for opposing the rotation of a reel with a force which is determined by the weight of the material on the reel and the speed of rotation thereof.

Another feature of the invention is an adjustable bearing for a reel by means of which the friction exerted upon said reel may be controlled.

Other objects and features of the invention will be apparent as the nature of the invention is more fully disclosed.

The invention also consists in certain new and original features of construction and combinations of parts hereinafter set forth and claimed.

Although the novel features which are be-

lieved to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an end elevation of a portion of the projection head of a motion picture projection machine showing the upper film magazine;

Fig. 2 is a side elevation thereof;

Fig. 3 is a side elevation of the closure for the film magazine;

Fig. 4 is a longitudinal sectional view of the frictional take-up device applied to the shaft of the upper film reel;

Fig. 5 is a section taken on the line 5—5 of Fig. 4;

Fig. 6 is a section taken on the line 6—6 of Fig. 4; and

Fig. 7 is a section taken on the line 7—7 of Fig. 4.

Like reference characters denote like parts in the several figures of the drawings.

In the following description and in the claims parts will be identified by specific names for convenience, but they are intended to be as generic in their application to similar parts as the art will permit.

Referring to the drawings more in detail, the invention is shown specifically as applied to a motion picture projection machine having a projection head 10 (Figs. 1 and 2), a housing 11 and an upper film magazine 12. The particular form of projection head forms no part of the present invention and has not been set forth in detail. Film magazine 12 is supported from housing 11 in any suitable manner and includes a door 13 which is hingedly supported as by hinge 14 (Fig. 2). A glass window 15 may be included in said door to allow the operator to observe the amount of film on the reel, at any particular instant. A suitable latch 16 may be provided for securing door 13 in closed position.

Referring to Fig. 4, the reel 20, which may be of any suitable form, is mounted upon

shaft 21 which is rotatably secured in housing 11 by an adjustable bearing. Said bearing comprises a slidable sleeve 22 carrying a cupped flange 23 which is mounted on shaft 21 and keyed to a suitable groove 24 therein as by adjustable key 25. Cupped flange 23 carries the inner ball race 26 with which balls 27 are in contact.

Outer ball race 30 is carried in sleeve 31 against shoulder 32 thereof and is secured by a tubular member 33 which is threaded into said sleeve 31 and bears against said ball race 30. Sleeve 33 is provided with a circular groove 35 in which thumb screw 36 is adapted to seat for locking said tubular member in position. Thumb screw 36 extends through an elongated slot 37 in housing 11 and serves as a handle for longitudinally adjusting the bearing with respect to both shaft 21 and said housing.

A grease cup 40 is positioned in housing 11 in communication with a groove 41 in sleeve 31. Oil is applied to the bearing from grease cup 40 through groove 41 and bore 42 and is discharged around shoulder 43 of sleeve 31, thence through groove 44 and bore 45. Pin 46 is secured in sleeve 31 and is adapted to slide in groove 44 in accordance with the longitudinal position of said bearing. Oil guard 50 is pinned to shaft 21, as by pin 51, and is provided with oil threads 52 which prevent oil from creeping along the surface of shaft 21 into the film magazine. Oil shield 53 is secured to the wall of said magazine and extends into a position closely adjacent oil guard 50 for preventing a direct passage of oil into the film magazine.

Oil guard 50 is also provided with suitable holes 54 which are adapted to receive pins 55 carried by the reel for rotatably securing the reel on shaft 21. The reel is secured on shaft 21 by a reel lock 56 which is pivotally mounted as by pin 57 to the end of said shaft and bears against a spring pressed 45 detent 58 which is secured in a suitable bore therein. Shaft 59 of reel block 56 is so formed as to exert a cam action against said detent whereby it is securely held either in extended or in locking position.

Brake housing 60 is formed with a hub member 61 which is in sliding engagement with a bore in housing 11. Said hub is provided with a circular groove 62 which is adapted to contact with a deformed bolt 63 by means of which the brake housing 60 is secured in housing 11. Bolt 63 (Fig. 6) is provided with a curved recess 64 which is adapted to be drawn against hub 61 for locking the brake housing in position. Slot 65 communicates with groove 62 and permits the brake housing to be withdrawn when said slot is rotated into a position adjacent bolt 63.

Longitudinal movement of shaft 21 is prevented by a thrust bearing comprising a block

70 which is secured to shaft 21 by pin 71 and bears against a stationary block 72 which is in rigid frictional engagement with hub 61 of brake housing 60. Brake drum 73 is provided with a hub member 74 which is secured to shaft 21 by pin 75. Drum 73 is formed slightly smaller than the interior of brake housing 60 and is adapted to rotate freely therein. Block 72 is provided with an elongated slot 76 through which shaft 21 extends whereby vertical movement of said shaft is permitted within a limited range.

The brake mechanism comprises friction blocks 80 which are mounted on yoke 81 and extend through suitable apertures in brake housing 60 into contact with brake drum 73. Yoke 81 is carried on threaded bolt 82 which is secured in said brake housing and may be adjusted with respect thereto by means of threaded nut 83 which is carried on said bolt 82 and lock nut 84 which cooperates therewith. The elevation of friction members 80 with respect to the brake housing may be controlled by suitable adjustment of yoke 81.

It is to be noted that the weight of the reel causes shaft 21 to pivot about the slidable bearing as a fulcrum, thereby tending to urge brake drum 73 into contact with friction blocks 80. The amount of friction which is exerted by said blocks is determined by the weight of the material on reel 20. Hence, the maximum amount of friction will be applied when a full reel is positioned on shaft 21 and this friction will be progressively decreased as the film is unwound.

Since the film travels at a constant speed the reel must rotate at a speed which is dependent upon the diameter of the film which is carried thereon. This is accomplished in accordance with the present invention by decreasing the friction on brake drum 73 as the weight of the reel decreases thereby permitting the reel to rotate at a faster speed.

The amount of friction applied to the brake drum may be manually regulated by varying the elevation of friction blocks 80 as above pointed out and may also be controlled by longitudinally varying the position of the slidable bearing with respect to shaft 21. When said bearing is moved toward the brake drum the length of the lever arm supporting the reel is increased and the length of the arm between the bearing and the brake drum is decreased. A given weight of reel accordingly causes the brake drum to bear against friction blocks 80 with a greater force. By suitably designing the above elements the friction device may be made to operate as a brake for stopping the operation of the reel when the bearing is adjusted to its extreme position. This feature may be utilized when it is desired to quickly stop the reel for any reason, such as breakage of the film.

The oiling means above described permits oil to be applied to the bearing regardless

of the longitudinal position thereof and at the same time prevents the oil from being applied to the film magazine where it could come in contact with the projection film.

5. It is to be noted that in the mechanism above described, not only is the friction applied to the reel regulated automatically in such manner that a substantially constant tension is maintained on the film, but a readily accessible manual adjustment is provided whereby the apparatus may be readily adapted to any particular type or size of reel.

10 The invention has been shown as applied to the upper film magazine of a projection machine, but it is not limited thereto. It may also be applied to the lower film magazine or to other reeling devices as will be apparent to a person skilled in the art.

15 While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a reeling device, a rotatable shaft, a retarding means and a reel carried on said shaft, a bearing for said shaft positioned between said retarding device and said reel, said bearing being adapted to permit pivotal movement of said shaft about said bearing as an axis in response to the weight of material on said reel, and means for longitudinally moving said bearing to vary the position of said axis with respect to said retarding device and said reel.

20 2. In a reeling device, a shaft for supporting a reel, a bearing intermediate the ends of said shaft for rotatably mounting the same and for permitting pivotal movement thereof about a horizontal axis, a brake drum and a reel carried by said shaft at opposite sides of said bearing, a friction device, and means whereby the weight of said reel causes pivotal movement of said shaft about said axis, said pivotal movement altering the transverse position of said brake drum with respect to said friction device, whereby the amount of friction therebetween is controlled.

25 3. In a reeling device, a shaft for supporting a reel, a bearing for rotatably mounting said shaft and for permitting pivotal movement thereof about a horizontal axis, a brake drum carried by said shaft, a friction device carried by said brake drum and means whereby the weight of said reel causes pivotal movement of said shaft for bringing said brake drum into engagement with said friction device, whereby the rotation of said shaft is opposed, and means for longitudinally moving said bearing for varying the ratio between the weight of said reel and the pressure exerted by said brake drum.

4. In combination with a housing, a bearing slidably mounted therein, a shaft rotatably mounted in said bearing and extending on opposite sides thereof, means for supporting a reel on one end of said shaft, a brake drum mounted on the other end thereof, a friction element carried by said housing in a position to cooperate with said brake drum for opposing rotation of said shaft, and means for varying the position of said bearing whereby the effective lever arms between said bearing and said reel and said brake drum respectively may be adjusted.

5. In combination with a housing, a bearing slidably mounted therein, a shaft rotatably mounted in said bearing and extending on opposite sides thereof, means for supporting a reel on one end of said shaft, a brake drum mounted on the other end thereof, a friction device carried by said housing in a position to cooperate with said brake drum for controlling rotation of said shaft, and means for varying the position of said friction device for controlling the amount of said friction, and means for varying the position of said bearing whereby the effective lever arms between said bearing and said reel and brake drum respectively may be adjusted.

6. In combination with a projection machine, a housing, a film reel, means for supporting said reel comprising a shaft rotatably mounted in said housing a bearing for said shaft carried in said housing, means for longitudinally moving said bearing, a brake drum associated with said shaft, means responsive to the weight of said reel for exerting frictional force against said brake drum, and means for adjusting the amount of said force.

7. In combination with a rotatable shaft, a housing, a bearing for supporting said shaft in said housing comprising a sleeve carried by said shaft and slidably thereon, a second sleeve mounted in said housing and slidably therein, a handle associated with said second sleeve and extending through a slot in said housing for adjusting the longitudinal position of said bearing, an oil guard mounted on said shaft for limiting the longitudinal movement of oil, oiling means comprising a slot in said second sleeve communicating with said bearing, a brake drum mounted on said shaft, friction members carried by said housing, and means for varying the position of said members with respect to said brake drum for adjusting the friction thereof, said shaft being adapted to pivot vertically about said bearing whereby the weight of material supported thereby is caused to bring said brake drum into engagement with said friction members.

8. In a reeling device, a rotatable shaft adapted to support a reel, means for pivotally mounting said shaft for movement about a fulcrum intermediate the ends thereof,

means whereby the weight of material on said shaft causes said pivotal movement, a friction element and a reel carried by said shaft on opposite sides of said mounting, means whereby pivotal movement of said shaft causes movement of said friction element transverse to the axis thereof, and means for frictionally controlling the rotation of said shaft in accordance with the transverse position of said friction element.
